UNITED STATES PATENT OFFICE.

JOHN H. STONEMETZ, OF ERIE, PENNSYLVANIA.

PERFECTING PRINTING-MACHINE.

SPECIFICATION forming part of Letters Patent No. 252,153, dated January 10, 1882.

Application filed April 14, 1881. (No model.)

To all whom it may concern:

Be it known that I, JOHN H. STONEMETZ, a resident of Erie, Erie county, Pennsylvania, and a citizen of the United States, have invented new and useful Improvements in Perfecting Printing-Machines; and I do hereby declare that the following is a full, clear, and exact description thereof, reference being had to the accompanying drawings and the letters or figures of reference marked thereon.

My invention relates to what are known as "web perfecting printing-presses;" and it consists in various improvements thereon, as will hereinafter be fully described and pointed out. Many of the said improvements are not, however, limited in their functions to a web-press nor to a perfecting-press, but are susceptible of use on various forms of presses.

My invention is illustrated in the accompanying drawings as follows:

Figure 1 is a perspective view. Fig. 2 is a longitudinal vertical section. Fig. 3 is a like view to Fig. 2, but shows an alternative mechanism for operating the sheet receiving and delivering rack.

The parts shown are designated by letters of reference as follows:

A A, &c., are the main or central frame, and A' is the arch or upper part thereof. These sustain and support the type-cylinder and the impression-cylinders.

B B, &c., are the frame-work, holding the feeding, reversing, and folding devices which accompany one impression-cylinder. It is attached to and forms a wing upon the central frame, and is to be duplicated around the central frame as impression-cylinders are added, one of which only is shown in full.

C is the type-cylinder, and also bears the inking-distributing plate N and the forms F in turtles f.

D D, &c., are impression-cylinders, of which the drawings indicate places for two in Fig. 1, and four in Fig. 2, but only show one in full.

E is the driving-gearing. C' and D' are the gearings respectively of the type cylinder and the impression-cylinder, and they bear such a relation to each other that the impression-cylinders revolve three times to the type-cylinder's once, thus afford-

ing one revolution for each printing-space F and one for the ink-space N.

G G are the type-inking rollers. H H' are the feeding and cut-off rollers. I, I', I'', and I''' are also ink-rollers.

W is the ink-well; P, the web of paper; T, the table or paper-way, over which the sheets pass upon tapes or by other means on their way from the feeding-rollers to the impression-cylinders.

S is a detached sheet making the passage.

J is a vibrating or tilting rack for receiving the sheet when printed on one side and delivering it at a feeding-point for being taken by the grippers of the impression-cylinder and perfected.

K K' K'' are folding-rollers for folding the sheets when printed.

Most of the parts of my machine are in and of themselves old, and their construction need not be described.

The following description will enable those skilled in the art to which my invention relates to make and use the same.

The frame-work of my machine is made in sections. Thus, A A, &c., are the central frame, made very strong and secure, so as to properly hold the type-cylinder, the various impression-cylinders, ink distributing and applying rollers, and operative gearing. In Fig. 80 1 this frame-work is shown as adapted to receive two impression-cylinders upon the part A, while in the other figure the arch A' is shown as adapted also to receive two impression-cylinders, making four in all. The bearings or 85 boxes of the impression-cylinders sit in the sockets a a a a. This frame-work may, by proper enlargement and change of form, be adapted to receive more than four such cylinders. A wing-frame, B, is to be provided for each impression-cylinder. I show but one, but the duplication of the same for each impression-cylinder is the work of a mechanic. These frames contain and support the feeding, reversing, and folding mechanism accompanying each impression-cylinder.

The press may first be constructed precisely as shown in Fig. 1, i. e.—having only one impression-cylinder and one wing-frame, but having its frame A provided with sockets a, for

receiving a second impression-cylinder. When afterward it becomes necessary or desirable to enlarge the capacity of the machine the second impression-cylinder may be added, and 5 also a second wing-frame containing the necessary accompanying mechanism. If it is again found necessary to enlarge the capacity of the press, the arch shown in Fig. 1 is removed, and an arch such as is shown in Fig. 2 is substituted, and other impression-cylinders added, 10 together with wing-frames resting on the lower wing-frames. During the process of adding either of the above enlargements the press is in nowise disabled, but can be run at any time 15 during said operation.

The type-cylinder C is adapted to receive all the forms. They may be of type placed in turtles or of stereotype-plates. I expect, however, that the type-forms will generally be used, 20 as thereby the cost and time of making stereotype-plates will be saved.

The type-cylinder C, in addition to the forms, carries an ink-distributing plate, N, and as the impression-cylinders are geared to make three 25 revolutions to one of the type-cylinder, two of them occur over the forms and one over the ink-plate N; hence one of the revolutions of the impression-cylinders performs no work of impression, and is what I call a "blank" revolution. 30 It will be seen hereinafter that during this blank revolution the operation of reversing the sheet takes place. I make the ink-plate N detachable from the cylinder C, so that it can be easily cleaned by means of attaching-screws n.

The forms F sit in turtles f, as is common in many forms of machines of this character. The means I employ for attaching the turtles are, however, novel, and are as follows: The 40 outer edges of the turtles are beveled, so as to make the lower face of the turtle broader than the top. The adjoining edges of the ink-plate are beveled in an opposite direction, and a bar, e, across the face of the cylinder, which 45 fits the space between the turtles, is also beveled in an opposite direction from the bevel of the turtles, thus giving a dovetail effect. The turtles are put in place by sliding lengthwise of the cylinder into the space between the bar 50 e and the ink-plate N. Of course a form other than a bevel or miter may be given to the edges—as, for instance, a tongue and groove or a rabbet. The novelty consists in sliding the turtles into place lengthwise of the cylinder. 55 After the turtles are in place they are prevented from moving laterally by screws or jam-nuts. The advantage of this construction over the method of attaching by bolts and nuts, as is now practiced, is that there is no danger 60 of the turtles not being firmly attached, for they are attached as soon as in place, and cannot fall off if the cylinder accidentally turns, as sometimes occurs.

The feeding and cutting rollers H H' are of 65 common construction, and are operated from the shaft H², which connects by proper gear-

ing with the shaft of cylinder C, or, if desired, some other shaft. The sheet S, after being severed from the web, finds its way to the feeding-point of the impression-cylinder by means of 70 tapes or any convenient mechanism for conveying sheets.

One pair of cutter-rollers may be made to serve for supplying sheets to more than one impression-cylinder by properly timing their 75 movement and supplying two carrying devices and an automatic deflector for changing the direction of movement of the sheets.

The impression-cylinders are of common construction, and receive and present the paper 80 to the types in no novel manner.

The essential feature of my invention relates to the means for reversing the sheet after the first impression, or, in other words, to the means whereby, as the sheet has passed from the impression-cylinder head foremost, it is again fed directly to the press tail foremost, and hence in position to print the reverse side, or, as it is known to the trade, "perfected," thereby causing both impressions to be made upon one 90 impression-cylinder, or, if desired, upon two impression-cylinders, before the sheet leaves the machine. The means which I use to accomplish this result consist of appliances by which, after the sheet leaves the impression-cylinder 95 after the first impression, it is carried (lifted or depressed, as the mechanism may be arranged) past the center of motion of said cylinder, and thus brought to a position for being gripped at its tail end by the grippers of the cylinder and carried to the press for perfection; or if it is desired to use two cylinders, one for the first impression and one for the second, the said devices will carry the sheet from one 100 to the other.

The mechanism for reversing the sheet is as follows: J is a table or rack, which lies upon the rollers K, and is in position to and does receive the sheet after the first impression.

As soon as the sheet has left the cylinder and 110 passed upon the rack J it ceases to move, and stands with its tail end projecting off the end of the rack. As soon as the sheet has reached this position the rack tilts by means of the rod J', which connects with proper gearing at some 115 convenient point—as, for instance, the shaft of the cylinder C—moving the crank or bell-crank lever J". This movement carries the sheet up so that the end which sticks over the end of the rack is at the feeding-point. This position of the rack J is shown by dotted lines. (See Fig. 2.)

As soon as the impression-cylinder has made the blank revolution above named its grippers take the half-printed sheet from the rack J and carry it to the second form and perfect 125 it. During the operation of perfecting the sheet the rack J remains up until the sheet has passed sufficiently from the impression-cylinder to stand with its center over the space between the rollers K. Then the rack drops, and a projection, j, on its under side acts as a starter, and starts the sheet to doubling between the 130

rollers K. This last action is, however, for a four-paged sheet. If the sheet is eight paged, the gearings which regulate the movement of the rack J are so set as to allow the rack to

5 come down before the sheet begins to pass from the cylinder D, and a stop is fixed at the proper point, so that the projection j on the rack will not sit clear into the space between the rollers K, but will act as a deflector to turn the sheet 10 and cause it to pass between the rollers K and go to the rollers K' for the first fold.

The mechanism for reversing the sheet may be varied or modified. Thus, in place of a tilting frame a parallel-rising frame may be used 15 with oblique levers like the side of a parallel rule, which will, as it rises, move laterally and carry the sheets tail ends to the grippers. Such a construction is shown in Fig. 3, wherein J is the table or rack, as in the other figures.

20 1 and 2 are the arms. 3 is the rock-shaft; 4, the arm by which the rock-shaft is tilted; 6, a connecting-rod, and 5 the cam for operating the device. The table is shown in full lines as elevated and in the act of redelivering the 25 sheet tail foremost to the grippers. In dotted lines it is shown as down in position to receive a sheet after the first impression.

Much of the folding apparatus is not shown, but enough is shown to illustrate my invention; 30 and as the construction of said folder beyond its location forms no part of my invention it is deemed unnecessary to show more than is shown.

The ink-distributing roller I is on the main 35 driving-shaft of the press. This is very advantageous, as it requires no gearing, and hence there is no danger of breaking the same if the ink is too stiff, as is sometimes the case, especially in cold weather.

40 40 What I claim as new is—

1. In a perfecting printing-press, the combination, with the impression-cylinder thereof, of a sheet receiving and redelivering apparatus consisting of a rack or table which receives the 45 sheet head foremost as it leaves the impression-

cylinder after the first impression and while holding said sheet changes its position, substantially as described, and re-presents the said sheet tail foremost directly to the grippers for a second impression, substantially as set forth. 50

2. In a perfecting printing-press, the combination, with the impression-cylinder thereof, of a sheet receiving and redelivering apparatus consisting of a vibrating rack or table which receives the sheet as it leaves the impression-cylinder after the first impression head foremost and while holding said sheet by vibrating lifts it from the lower to the upper side of said cylinder and presents it tail foremost directly to the grippers for a second impression, 55 60 in a manner substantially as described.

3. In a perfecting printing-press, the combination of an impression-cylinder, a pair of folding-rollers, and a vibrating sheet receiving and redelivering rack or table which is provided 65 with a starter-projection on its lower side, said parts being constructed and arranged to operate in the manner and relation and for the purposes substantially as set forth.

4. In a printing-press, the type-cylinder C, 70 in combination with the ink-plate N and bar e, with inwardly-beveled edges, and turtles f, with outwardly-beveled edges, substantially as and for the purposes mentioned.

5. In a perfecting printing-press, the combination, substantially as shown, of the following elements: the type-cylinder C, with turtles f f, and ink-plate N, impression-cylinder D, feeding-rollers H H', with cut-off knife h, sheet-way T, tilting rack or table J, with starting 80 and deflecting projection j, and folding-rollers K K' K".

In testimony that I claim the foregoing I have hereunto set my hand this 26th day of March, 1881.

JOHN H. STONEMETZ.
